UNITED STATES PATENT OFFICE.

MOGENS FARCH, OF CLEVELAND HEIGHTS, OHIO, ASSIGNOR TO THE W. S. TYLER COMPANY, OF CLEVELAND, OHIO, A CORPORATION OF OHIO.

ELEVATOR-CAR CONSTRUCTION.

Application filed July 11, 1925. Serial No. 42990.

The present invention, relating, as indicated, to elevator car construction, is more particularly directed to the provision in an elevator car of a relation between the necessary framework and the sides or panels which will permit interchangeability in the manufacture of cars and also allow for convenient removal of panels and the substitution of others in cars in use for the purpose of repair, refinishing and the like. A further object of the invention is the provision in an elevator car of an extremely simple construction of framework and panels which will permit the panels to be removably secured to the framework without showing the removability of these panels; in other words, a construction which will simulate the present car construction so closely that the individual panels which comprise the side walls of the car can almost instantly be removed and that this feature of the construction will not be noticeable to the ordinary user of cars. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is an elevation of one of the interior walls of my improved car; Fig. 2 is a vertical section through one of such walls; Fig. 3 is a horizontal section through a portion of the wall shown in Fig. 1, the section being taken on the line 3—3 in such figure; Fig. 4 is an enlarged sectional view showing the relationship between one of the removable panels and frame; Fig. 5 is a horizontal section through one wall and a corner of a modification of the construction of the preceding figures; Figs. 6, 7 and 8 are fragmentary sectional views showing various modifications of the foregoing construction; and Fig. 9 is a vertical section showing still another construction of frame and panel.

In the manufacture of elevator cars considerable difficulty and additional cost is experienced from the fact that in almost every building the architects design special fronts and cars, although the difference between these various designs lie chiefly in the treat-

ment given the various panels in the wall of the car, and in the molding, etc., rather than in the outline or shape of the car itself. The result, however, is that to the car manufacturers each order is distinct from every other order and there can be no uniformity in manufacture. A further objection is that when the inner panels of a car require refinishing it is necessary to take that car out of service for the period required to refinish the walls, and this period will many times be from a week to a month before the inner finish is dry and safe for use. It is to prevent both of these troubles in the manufacture and use of elevator cars that the following invention has been developed.

In Fig. 1 there is shown one wall of an elevator car which consists of three panels 1, 2 and 3, and it may be stated that the ordinary wall of an elevator car usually consists of two, three or four panels. These panels 1, 2 and 3 are set off from each other by intermediate moldings or so-called trim strips 4 and 5, and correspondingly treated moldings or trim strips are employed at the two corners of the wall, as shown in this figure. In Fig. 3 I have shown a framework to which the panels may be applied, the framework consisting of angular uprights 6 and 7 which are secured to the platform of the car by means of members 8, which are shown in Fig. 2. Each of the members 6 and 7 is provided with a recessed portion or socket 9, and it is in front of and substantially within this recessed portion that the removable panel is to be placed.

Removably secured to the members 6 and 7 are corner frames 10, by means of screws 11. These corner frames are constructed as shown in the form of unitary combination ornamental trim and lock strips and are adapted to position against the surface 12, on the members 6 and 7, the edges of rectangular frames 13 in which the removable panels are secured. Thus each of the members 13 is provided with an outer surface 14 in the form of a molding to set off the panel itself, and has a flat rear surface which is adapted to clamp against a suitable strip 15 mounted against the recessed portion 9 of the upright 6, a panel 16, which may be painted or varnished in any manner desired to give a harmonious appearance with the trim strips 14 and the removable corner frames 10, which are similarly treated as at 17 to harmonize with the remainder of the entire panel. The members

13 will be understood from the above to combine means for engaging the panels and an ornamental molding for surrounding the edges of such panels. The outer extremities 5 of members 13, as seen in detail in Figure 4, are formed with rounded enlargements which are adapted to cooperate with complementary recesses on the rear surface of strips 13 and 19 to properly locate the panel in a horizontal 10 position.

The other edge of the same panel 16 is similarly clamped against the member 9 by means of a second molding member 18 which is removably held in position by means of a combined trim and lock strip 19, secured by means of screws 20 which engage another upright 15 21 nesting into the end 22 of the member 9 and forming a rigid support at the center of the wall of the car. Obviously, the entire 20 wall may be broken up by these means into any desired number of panels, and if the car itself were of small dimensions each wall surface might be treated as a single panel, although in ordinary cars each wall is divided 25 into either two or three panels.

The members 14 and 18 are connected at their top and bottom by means of corresponding strips 24 and 25, to which the panel 16 is also secured, and these members are clamped 30 between moldings 26 and 27, the surface of which may be formed to correspond with the moldings 10 and 19. These strips 26 and 27 are also removably secured, the lower one to a member 28, which forms the base element 35 of the wall of the car, and the upper member 27 to a strip 29 which is secured to an angle 30 extending across the roof of the car.

In Fig. 5 I have shown another construction in which removable panels 40 are secured 40 between frame members 41 and 42 by means of narrow strips 44 and bolts 43, the strips being slidably received within recesses 45 formed in the sides of the members 41 and 42. The member 41 is in this form shown as extending diagonally across the corner of the car where the panel-receiving portion is duplicated to receive the next adjacent panel of the other wall, and this member is removably secured against the corner frame member 46 of the car by suitable bolts, which are not shown. If two panels are employed in one wall of this construction a member 42 is provided which has oppositely extending flanges 46, in each of which is secured one 55 of the panels 40 in the manner already described.

This same construction may be employed either with sheet metal panels, such as is shown in Fig. 5, or with panels of other material, such as a combination wood and asbestos panel, shown in Fig. 6, in which the inner layer of the panel is wood 50, behind which is mounted a layer of asbestos 51 which is in turn secured to a steel plate 52.

65 In Fig. 7 there is shown a panel consisting

of a glass plate 55 backed up by a layer of asbestos 56, which is secured in turn to a steel plate 57, while in Fig. 8 I have shown a panel consisting of wood 59, asbestos 60 and a back-up plate 61, the surface of the wood 59 being covered by leather, cretonne or any other material which may be desired to give a certain interior appearance and finish. All of the panels shown in Figs. 5, 6 and 7 are of substantially the same total thickness, that is, the ends of the panel 40, in Fig. 5, are rebent 70 to form flanges 63, and the depth of this panel at this point is the same as that of the panel shown in the following figures so that any of these panels may be interchangeably used in the frames 41 and 42 without any change except the removal of one panel and the substitution of another.

In Fig. 9 I have shown the means for securing the top and bottom of the panels shown in Figs. 5 to 8, the panel 40 being provided with similar top and bottom flanges 65 and 66 which are secured against inwardly extending flanges 67 on horizontal frame members 68 and 69, the outer one of which is secured to the roof of the car, while the lower one is mounted upon the base member 70 of the wall.

The present construction makes it possible for the elevator car manufacturers to build and keep in stock a minimum number of car frames which can be fitted together to provide the frame of a car upon which any of a great number of different kinds of panels may be used. The economy of this type of car will 95 of course be apparent, while the saving in use of a car so constructed, and in which all of the panels may be removed at any time for repairing or refinishing, during which time another set of panels may be fitted into place 100 and this in turn removed and used in the next car while the panels of that car are being refinished.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A wall construction for elevator cars comprising spaced parallel frame members provided with panel receiving sockets, a panel removably disposed between said frame members in said sockets, and panel retaining strips removably secured to said frame members in position to engage and retain in position said panel, said strips consisting of a unitary combination ornamental trim and lock strip.

2. A wall construction for elevator cars comprising spaced parallel frame members, socket strips disposed against said frame 125

members, a panel disposed against said strips, and means for locating said panels horizontally and removably securing the same to said socket strips.

5. A wall construction for elevator cars comprising spaced parallel frame members, socket strips disposed against said frame members, a panel disposed against said strips, said panel having its side edges enlarged and 10 removable retaining strips secured to said socket strips having wedge shaped surfaces to engage said enlarged edges of the panel to locate the same in a horizontal plane.

4. A wall construction for elevator cars 15 comprising spaced parallel frame members provided with panel receiving recesses, a panel removably disposed between said frame members in said recesses, the outer surface

of which falls substantially within the plane of said frame members, and panel retaining strips removably secured to said frame members, said strips comprising unitary ornamental trim and locking members.

5. A wall construction for elevator cars comprising spaced parallel frame members 25 provided with panel receiving sockets, a panel removably disposed between said frame members and having its outer edges reinforced by ornamental strips and combination ornamental trim and locking strips re- 30 movably secured to said frame members engaging said panel edges to hold the same in place.

Signed by me, this 10th day of July, 1925.

MOGENS FARCH.
